[57] CLAIM

The ornamental design for combined hose-attached
telescoping pressure sprayer and connector for attachment
to an additive fluid dispenser, as shown and de-
scribed.

DESCRIPTION

FIG. 1 is a top perspective view of a combined hose-
attached telescoping sprayer and connector for attachment
to an additive fluid dispenser showing our new
design in an essentially collapsed position;

FIG. 2 is a side elevational view thereof, the opposite
side being a mirror image;

FIG. 3 is a bottom plan view thereof;

FIG. 4 is an end elevational view thereof;

FIG. 5 is an opposite end elevational view thereof; and
FIG. 6 is a top perspective view thereof, shown in a
rotated and extended position.

The partial broken-line showing of the additive fluid
dispenser in FIGS. 1 and 2 is for illustrative purposes
only and forms no part of the claimed design.
